UNITED STATES PATENT OFFICE.

JAMES H. VAN DORN AND JOHN T. WHITEHOUSE, OF CLEVELAND, OHIO, ASSIGNEES
TO THE VAN DORN IRON WORKS COMPANY, OF CLEVELAND, OHIO, A CORPORATION
OF OHIO.

LOCK-BOX MECHANISM FOR JAIL-CELLS.

1,110,470.

Specification of Letters Patent. Patented Sept. 15, 1914.

Application filed August 18, 1913. Serial No. 785,274.

To all whom it may concern:

Be it known that we, JAMES H. VAN DORN and JOHN T. WHITEHOUSE, citizens of the United States, and residents of Cleveland, in the county of Cuyahoga and State of Ohio, have invented a certain new and useful Improvement in Lock-Box Mechanism for Jail-Cells, of which the following is a full, clear, and exact description.

10 In a familiar form of jail construction there is a tier or row of cells, in front of which is the prisoners' corridor; and at one end of the row of cells and prisoners' corridor and separated from the latter by a 15 grating, is the jailer's corridor. In this jailer's corridor are the operating members of mechanisms by which an attendant may simultaneously open or close all of the doors of a tier of cells, and separately lock and unlock the various cell doors; and also, generally, there is a so-called lock box within which are placed some or all of these operating members and some of the mechanism which they move in order that they may be 20 accessible when and only when the door of the lock box is open.

This invention is especially adapted for use in connection with jail construction having the above mentioned characteristics.

30 The objects of this invention are, first, to minimize the chance that the jailer will neglect to close all of the doors of a tier or row of cells at the appointed time. Second, to enable a jailer or inspector to observe from any part of the jailer's corridor whether the cell door controlling mechanism has or may have been left, by design or neglect, in a position such as permits the cell doors or any of them to be opened. Third, to render it 35 impossible to move the cell door controlling mechanism in the door opening direction without first opening the door of the lock box.

The invention consists in the construction 45 and combination of parts which are herein-after described and definitely pointed out in the appended claims, and are illustrated in the accompanying drawing, in which—

Figure 1 is a front elevation of two cells 50 of a tier of cells, showing also the lock box connected with the end wall of the end cell. Fig. 2 is a vertical section through the lock box and through some of the cell door operating mechanism above the lock box. Fig.

3 is a sectional plan view in the plane indicated by line 3—3 on Fig. 2, when the lock box door is opened; and Fig. 4 is a sectional plan view in the plane indicated by line 4—4 on Fig. 2 when the lock box door is closed.

Referring to the parts by letters, A represents the lock box. This is located in the jailer's corridor, and is secured to the end wall of the end cell of a tier of cells. This lock box contains the mechanism, or some of the mechanism through which the opening 60 and closing and locking of the cell doors is accomplished.

A shaft B is mounted in said lock box and projects out of the same, and has an operating handle b secured to its projecting outer 65 end. It is by the rocking of this shaft in one direction or the other that the jailer is able to simultaneously open or close all of the doors of the tier or cells. What form of door moving mechanism is operated by this 70 rock shaft is not material to this invention. Such mechanism may be like that shown in Letters Patent No. 1,007,316, granted October 31, 1911, to Van Dorn and Whitehouse for prison cell door mechanism. That is to 75 say, a gear b¹ fixed to the rock shaft B within the lock box may mesh with the lower rack teeth c on a vertically movable rack bar C which is in the lock box. Other rack teeth c¹ on the lower part of said rack bar engage 80 a gear d fixed to a rock shaft D which is mounted in the upper part of the lock box, and has on one end a crank arm d¹. The bar F which is pivotally connected with this 85 crank arm has a gear f mounted on its other end; and this gear engages with a fixed horizontal rack f¹, and with a rack g on the sliding pull bar G. This pull bar has notches 90 g¹ which severally receive bolts H carried by the several cell doors. Through the above 95 described train of mechanism as shown and described in the above mentioned prior patent, or some other suitable train of mechanism the rocking of the rock shaft B may cause the simultaneous closing or opening of all of the cell doors in the tier, or, at least, all of those doors whose bolts H are in engagement with 100 said notches g¹.

The lock box A has a swinging door a, which may be closed and locked. When the 105 cell door operating mechanism has been moved so as to open all of the cell doors, the operating lever b extends upward from the

shaft B. By swinging this lever so that it extends in a vertical position downward the door closing mechanism will be moved so as to close all of the cell doors.

5 Within the lock box is some of the mechanism by which any cell door may be independently unlocked or locked, and by which also the bolt H carried thereby may be disengaged from the pull bar. What form this 10 particular mechanism may have is not material to the present invention. This mechanism, whatever may be its character, is not accessible when the lock box door is closed. 15 J represents a sliding bolt which is mounted in the lock box, but is capable of being projected out into the path of the operating lever b. This bolt is under the influence of a spring j which acts to move said bolt in,—that is to say, out of the path of said 20 lever; but such movement is sometimes prevented by the action of a latch bar M. This latch bar is in the lock box, and when permitted so to do will move by gravity downward so that its lower end will engage a 25 notch j¹ in the bolt, when the bolt J has been drawn back out of the path of lever b. Within the lock box is also a bell crank lever N which is pivoted on a vertical axis. The forwardly projecting arm of this bell 30 crank lever has a pivotal connection with the bolt J. The other arm which extends to the left from its pivot has a pivotal connection with a sliding bar P which projects horizontally forward so that its front end 35 is in the path of the lock box door a,—that is, it is in such position that the lock box door will strike it as it is moved toward the closed position. When the bolt J is drawn back so as to permit the lever b to swing, 40 and when this bolt is latched back by means of the latch M referred to, this bar will project so far forward, as shown in Fig. 3, that the lock box door will strike it before it is closed, and will be thereby prevented from 45 closing.

Whenever the lock box door is opened, the spring j operating on bolt J will move it and the bell crank lever N and bar P into the positions referred to; that is to say, the 50 bolt J will be drawn back into the lock box, and the bar P will be moved forward. Now lever b may be swung from its downward direction into its upwardly extended direction, and thereby all of the cell doors will 55 be opened. As soon as the lever b begins to swing in the door opening direction the rack bar C in the lock box will begin to move down. As it so moves, it carries down the finger c² which is fixed to the rack bar C, 60 and which, by engaging the finger m on the latch M has held said latch up. The latch M, when so released, will fall down into the notch j¹ in the bolt J; and thereafter any movement of the bolt J or the parts attached 65 thereto will be prevented. The jailer can

not close the lock box door because, as said door moves toward the closing position it will strike the now immovable bar P.

When, however, the jailer moves the operating lever b down to close all of the cell doors, he moves the rack bar C up. This rack bar carries a finger c². The latch M also carries a finger m which lies in the path of the finger c². When, therefore, the rack bar has just about reached the position it occupies when the cell doors are completely closed, the finger thereon will engage the finger on the latch and will lift it and thereby the bolt J and the parts connected therewith will be freed from restraint. Having 75 shut the cell doors, it is the duty of the jailer to see that the mechanism which controls the cell locks is in proper condition. Next, it is his duty to shut the lock box door. As he shuts it, the door, by engaging bar 80 P, will move it inward, thereby rocking the bell crank lever N and thereby pushing bolt J out in front of lever b, where it serves to prevent any such movement of this lever in the direction to open the cell doors, so 85 long as the lock box door a remains closed. 90

When any jailer or inspector looks at the lock box and sees that it is closed, he knows that the door closing mechanism must have been operated in the direction to close the cell doors. When he sees this lock box door open, he knows that the door closing mechanism may not have been moved so as to open the proper position, and it is his duty to see that it is in the proper position, and to then 100 close the lock box door. When this is once closed and locked, the cell door operating mechanism can not be moved so as to open the cell doors. Or, in other words, the lock box door cannot be closed until all of the 105 cell doors are closed, and the cell doors cannot be opened as long as the lock box door remains closed.

Having described our invention, we claim:

1. In jail construction, the combination of 110 the sliding doors of a row of cells, means operable from the end of said row for simultaneously opening and closing all of said doors, and a lock box having a door, with means which prevent the closing of the lock box door until the door operating mechanism has been moved to the door closing position and which prevents the door operating mechanism from moving from said position while the lock box door is closed. 115

2. In jail construction, the combination of 120 the sliding doors of a row of cells, means operable from the end of said row for simultaneously opening and closing said doors, which means include an operating lever, and a lock box having a door, with a sliding bolt in said lock box adapted to be projected into the path of said operating lever, and a forwardly sliding bar whose front end is in the path of the lock box door, 130

and mechanism connecting said bolt and bar and compelling their simultaneous movement one out and one in.

3. In jail construction, the combination of 5 the sliding doors of a row of cells, means operable from the end of said row for simultaneously opening and closing said doors, which means include an operating lever, and a lock box having a door, with a 10 sliding bolt in said lock box adapted to be projected into the path of said operating lever, and a forwardly sliding bar whose front end is in the path of the lock box door, and mechanism connecting said bolt 15 and bar and compelling their simultaneous movement one out and one in, a latch acting to prevent the inward movement of said bar, and means operable by the door operating mechanism as it moves to the door closing 20 position for withdrawing said latch.

4. In jail construction, the combination of 25 the sliding doors of a row of cells, means operable from the end of said row of cells for simultaneously opening and closing said doors, which means include an operating lever, and a lock box having a door, with a sliding bolt in said lock box adapted to be projected into the path of said operating lever, a forwardly sliding bar whose front 30 end is in the path of the lock box door, mechanism connecting said bolt and bar and compelling their simultaneous movement one

out and one in, a latch acting to prevent the inward movement of said bar, means operable by the door operating mechanism as 35 it moves to the door closing position for withdrawing said latch, and a spring acting to draw said bolt inward when the lock box door is opened.

5. In jail construction, the combination of 40 the sliding doors, of a row of cells, a train of mechanism operable from the end of said row of cells for simultaneously opening and closing said doors, and a lock box having a door, with a bolt movable into and out of 45 the path of a member of the train of door operating mechanism, a movable device which projects into the path of the door of the lock box, mechanism connecting said device and bolt and compelling their simultaneous movement one out and one in, a latch acting to prevent the outward movement of the bolt, and means operable by a 50 part of the train of door operating mechanism as it moves in the door closing direction for withdrawing said latch.

In testimony whereof, we hereunto affix our signatures in the presence of two witnesses.
